UNITED STATES PATENT OFFICE.

CARL LANGER, OF CLYDACH, ENGLAND, ASSIGNOR TO THE MOND NICKEL COMPANY, LIMITED, OF WESTMINSTER, ENGLAND.

APPARATUS FOR OBTAINING NICKEL FROM NICKEL CARBONYL.

No. 825,844.

Specification of Letters Patent.

Patented July 10, 1906.

Application filed July 8, 1905. Serial No. 268,858.

To all whom it may concern:

Be it known that I, CARL LANGER, manufacturing chemist, a subject of the King of Great Britain, residing at Ynyspenllwch, 5 Clydach, in the county of Glamorgan, England, have invented certain new and useful Improvements in Apparatus for Obtaining Nickel from Nickel Carbonyl, of which the following is a specification.

In specification to United States Letters Patent No. 606,843 is described apparatus for obtaining nickel from nickel carbonyl by passing the vapor of the latter through nickel in the form of shot or pellets kept at a temperature of about 200° centigrade. The nickel deposits from the vapor on the shot, which gradually increase in size. For the proper working of the apparatus it is essential that the pellets should be as nearly as possible at the same temperature at all parts of the vessel containing them, which is preferably a cylinder. If this is not the case, the nickel-carbonyl vapor may pass among the colder pellets without being decomposed, and nickel will be deposited on the hot surface of the cylinder. Moreover, the hotter pellets may decompose the carbon monoxid, causing a deposit of carbon on the nickel. Even when the cylinder is uniformly heated it not infrequently happens that owing to an increased rate of passage of the vapor or to a drop of the temperature of the pellets from some cause undecomposed vapor arrives at the outlets and, becoming heated in the neighborhood thereof, blocks them, causing a stoppage of the working.

The present invention relates to improvements in the said apparatus whereby the temperature of the pellets may be better controlled and made more uniform and danger of deposition of nickel about the outlets of the apparatus may be avoided. For these purposes each vessel or cylinder is heated by a number of gas-flames, preferably evenly distributed around the outside of the cylinder. The latter may be made with projections or ribs to form, with the outer casing, chambers to contain the gas-jets. The part of each cylinder where the escape of gases occurs is formed as an annular chamber through which a cooling gas or liquid may be circulated, and the escape-pipe for the gases passes through the said chamber. In this manner the parts of the cylinder immediately

around the outlet are kept sufficiently cool to 55 avoid decomposition of any nickel-carbonyl vapor which may escape.

The accompanying drawings illustrate one form of construction according to the invention.

Figure 1 is a vertical section of the apparatus wherein the nickel carbonyl is decomposed. Fig. 2 is a vertical section of one of the cylinders of the apparatus drawn to an enlarged scale. Fig. 3 is a section on line 3 3 65 of Fig. 2, and Fig. 4 is a cross-section of the hollow ring which is placed between each cylinder and that next it.

A is a cylindrical vessel built up of cylinders c, each of which has an upper flange f 70 and a lower flange f'. In building up these cylinders to form the vessel A a hollow ring w, having an inlet w' and an outlet w'', is laid upon the upper flange f of the cylinder c, which is to be the lowest, and on the top surface of this ring is supported the lower flange 75 f' of the next higher cylinder c, and so on. The innermost diameter of ring w is the same as the inner diameter of the upper part 80 of cylinder c, and there is a pipe m passing through the hollow ring, so that when the ring is in place it forms a hollow walled continuation of the cylinder c, from which the pipe m forms an outlet. To keep a free passage within this continuation of cylinder c, 85 the lower end of the cylinder next above it is reduced in diameter to form a deflecting-surface a'.

The cylinders c are cast with ribs c², preferably in axial planes of the cylinder, as here 90 shown, and these ribs form, with an outer cylindrical casing o, chambers a, in each of which is a small gas-burner b, supplied from a gas-pipe g, surrounding the cylinder. The top closure of the chamber a is a flange h, perforated to form an outlet l for each chamber. The space between the flanges h and f being also closed by the casing o forms a flue 95 through which the products of combustion escape to the chimney k', Fig. 3. There is a 100 space below the gas-pipe g for the supply of air to support the combustion of the flames of the burners b. A jacket o' for receiving a non-conducting lagging is generally provided. The pipes m open into a flue n common to 105 them all. The nickel carbonyl is passed into the vessel A by pipe y, which is closed at its lower end and has outlets x, situated beneath

hoods *z*, which prevent them from becoming blocked up.

As described in the aforesaid specification, the nickel pellets with which the vessel is filled are kept in continuous movement by being removed from the bottom of the vessel by a suitable conveyer *t* and reintroduced into the top of the vessel by a conveyer *v*.

The temperature of the vessel is kept at that most suitable for the decomposition of nickel from the nickel carbonyl by adjusting the gas-flames proceeding from burners *b*, and the carbon monoxide which is liberated escapes through pipes *m* and flue *n*. In order that no nickel carbonyl shall be decomposed in the immediate neighborhood of the pipes *m*, and thus block up the passages, cooling gas or liquid is introduced at inlets *w* in rings *w* and allowed to flow away by outlets *w'*.

Having thus described the nature of this invention and the best means I know of carrying the same into practical effect, I claim—

1. In apparatus for obtaining nickel from nickel carbonyl, a number of superimposed vessels, a number of chambers around each vessel having no communication with the interior thereof, and gas-burners in the chambers.

2. In apparatus for obtaining nickel from nickel carbonyl, in combination, a number of superimposed vessels, external ribs on each vessel, a casing surrounding each vessel in contact with the said ribs, and chambers formed between the vessel and the said casing, which chambers have no communication with the interior of the vessel.

3. In apparatus for obtaining nickel from nickel carbonyl, in combination, a vessel, an outlet from the said vessel, and an annular

chamber surrounding that part of the said vessel where the outlet is situated.

4. In apparatus for obtaining nickel from nickel carbonyl, in combination, a number of superimposed vessels, and an annular hamber between each vessel and the one above it. 45

5. In apparatus for obtaining nickel from nickel carbonyl, in combination, a number of superimposed vessels, and a hollow ring between each vessel and the one above it. 50

6. In apparatus for obtaining nickel from nickel carbonyl, in combination, a number of superimposed vessels, a hollow ring between each vessel and the one above it, and a pipe leading from the interior to the exterior of the said ring through the hollow thereof. 55

7. In apparatus for obtaining nickel from nickel carbonyl, in combination, a number of superimposed vessels, a hollow ring between each vessel and the one above it, a pipe leading from the interior to the exterior of the said ring through the hollow thereof, an inlet into the hollow of the said ring, and an outlet from the hollow of the said ring. 60

8. In apparatus for obtaining nickel from nickel carbonyl, in combination, a number of superimposed vessels, a number of chambers around each of the said vessels, a gas-burner in each of the said chambers, an outlet to each of the said vessels, and an annular chamber surrounding each of the said vessels at the part thereof where the said outlet is situated. 65

In testimony whereof I have signed my name to this specification in the presence of two subscribing witnesses.

CARL LANGER.
